(57) **CLAIM**

The ornamental design for a display for a video conference system endpoint display and stand, as shown and described.

DESCRIPTION

FIG. 1 is a front perspective view of a video conference system endpoint display and stand;

FIG. 2 is a rear perspective view of a video conference system endpoint display and stand;

FIG. 3 is a front elevation view of a video conference system endpoint display and stand;

FIG. 4 is a rear elevation view of a video conference system endpoint display and stand;

FIG. 5 is a side elevation view of a video conference system endpoint display and stand;

FIG. 6 is a side elevation view of a video conference system endpoint display and stand;

FIG. 7 is a top plan view of a video conference system endpoint display and stand;

FIG. 8 is a bottom plan view of a video conference system endpoint display and stand;

FIG. 9 is a front perspective view of a video conference system endpoint display and stand;

FIG. 10 is a rear perspective view of a video conference system endpoint display and stand;

FIG. 11 is a front elevation view of a video conference system endpoint display and stand;

FIG. 12 is a rear elevation view of a video conference system endpoint display and stand;

FIG. 13 is a side elevation view of a video conference system endpoint display and stand;

FIG. 14 is a side elevation view of a video conference system endpoint display and stand;

FIG. 15 is a top plan view of a video conference system endpoint display and stand; and,

FIG. 16 is a bottom plan view of a video conference system endpoint display and stand.

Any portions shown using dashed lines are for illustrative purposes only and form no part of the claimed design.

1 Claim, 16 Drawing Sheets
